UNITED STATES PATENT OFFICE.

FORÉE BAIN, OF CHICAGO, ILLINOIS.

DESIGN FOR A FRAME FOR DYNAMO-MACHINES.

SPECIFICATION forming part of Design No. 25,366, dated April 7, 1896.

Application filed December 24, 1894. Serial No. 532,886. Term of patent 7 years.

To all whom it may concern:

Be it known that I, FORÉE BAIN, a citizen of the United States, residing at Chicago, in the county of Cook and State of Illinois, have 5 invented and produced a new and original Design for Frames for Dynamo-Electric Machines, of which the following is a specification.

My invention relates to the form or design 10 of a frame for a dynamo-machine.

Figure 1 is a side elevation, and Fig. 2 is an end elevation.

Like letters refer to like parts throughout the several views.

15 The subbase A of the frame is substantially rectangular in shape, as shown. Resting upon the subbase A is a cross-shaped or four-armed piece having the arms B B with round ends, as shown, and the substantially 20 rectangular-shaped arms C C. The upright supports D D rest upon the ends of said latter arms. Supported upon the arms B B are the columns E E, substantially cylindrical,

except where cut away and connected at the top by the cross-piece F, which is round at the 25 ends to correspond with the shape of the columns E E.

The essential features of my design, therefore, embrace the substantially rectangular base, the cross-shaped piece thereon having 30 upright supports resting on two of its arms, and the substantially cylindrical columns, supported by the other two arms, said latter arms being round at the ends, so as to conform to the shape of the columns, said columns being connected at the top by a cross-piece provided with round ends, as shown, to correspond therewith.

I claim—

35 The design for the frame of a dynamo-electric machine as herein shown and described.

FORÉE BAIN.
